TYPEWRITER

Seward A. Dean, St. Paul, and Obed M. Russell, Hastings, Minn., assignors of one-fourth to Arthur C. Cragg, one-fourth to Le Roy Welliver, and one-fourth to Roy F. Wilder, all of St. Paul, Minn.

Application April 20, 1932, Serial No. 606,352

2 Claims. (Cl. 197—5)

This invention relates to typewriters and more particularly to typewriters adapted to simultaneously print a plurality of originals or duplicates.

It is an object of our invention to provide a compact, efficient typewriter which will print simultaneously upon a single elongated sheet of writing material, or, if desired, upon a series of separate sheets, two or more columns of characters through the operation of a single set of keys.

10 It is a further object to provide a typewriter for special work wherein the platen or work holder may be automatically back-spaced and simultaneously elevated line by line by the depression of a single key and wherein a number of keys are provided, the operation of each being adapted to back space the platen a different predetermined distance while elevating the platen in each instance one line above its former position.

A further object is to provide an efficient typewriter for special use such as in printing bills where the numbers or items are disposed one above the other and wherein the variable back spacing functions automatically enable the numbers to be printed in the proper columns and wherein the platen in the printing of a number including a decimal figure will jump the decimal point space, disposing the decimal figure an extra space from the unit column and thus indicating the decimal.

30 Our improved typewriter is especially well adapted for making out duplicate bills on a single sheet of paper where a number of items in two or more columns are required, such as, for example, in preparing bills for the public utility companies where printed forms are utilized and it is impractical to make carbon copies.

In general, the embodiment of our invention illustrated in the accompanying drawings comprises a flat substantially vertical platen which is adapted to carry sheets or blanks to be printed in multiple and this platen is mounted for step by step movement for figure or letter spacing, governed by an escapement which is located as shown at the rear and lower portion of the platen carriage. The machine as shown is adapted to simultaneously print four duplicate columns of figures or characters and to this end four type baskets are provided, each type basket including an independent segment which is slotted for reception and pivotal connection of the type bars. The corresponding type bars of the several type baskets are connected to common operating members which, as shown, comprise rock shafts each controlled by the depression of an appropriate key lever so that when a key is struck the

four connected type bars all carrying a similar type character are simultaneously and forcibly swung against the sheet to be printed upon at spaced points thereon. The depression of the key lever operates a universal bar which extends rearwardly and around the lower platen support and which operates the escapement. As shown, the typewriter is adapted for special work in typing duplicate bills, the characters of course being in the form of figures which are arranged in four columns, one entry being properly disposed a line below the preceding one. The escapement wheel has one tooth removed so as to jump the space for the decimal point, thereby indicating decimal figures. The universal bar referred to actuates 15 mechanism for winding the typewriter ribbon from one spool to the other and further causes the ribbon to be moved laterally and upwardly slightly before the type strikes the sheet and to be subsequently withdrawn whereby the writing 20 is exposed after each character is printed. The typewriter also includes a suitable space bar for operating the escapement mechanism without actuating the type bars.

Mechanism is provided for elevating the platen 25 with the work sheet line by line and for simultaneously back spacing the platen as desired within a given range whereby the platen may be quickly and accurately set by the depression of a single key for starting the next entry to be made 30 in proper relation with the desired vertical column and upon the line below the previous entry made. The two movements of the platen referred to, to wit:—the line by line elevation and the back spacing, are effected by two associated 35 mechanisms both of which are actuated by the upward swinging of the inner or rearward end of any one of several platen setting key levers. Each of the said platen setting key levers is associated with the back spacing mechanism to 40 back space the platen a different distance than that effected by the other setting key levers and all of said key levers are associated with the platen elevating mechanism to raise the platen 45 one line at a time when any one of the setting keys are depressed.

In the embodiment of our invention illustrated in the accompanying drawings, like reference characters refer to similar parts throughout the 50 several views, wherein:—

Fig. 1 is a front elevation;

Fig. 2 is a top plan view of the machine, substantial portions of the top cover plates at the front and rear of the carriage being broken away 55

to show the working mechanism within the case or frame;

Fig. 3 is a vertical section taken on a plane disposed just forwardly of the rear cover plate of the case and showing most of the working parts in rear elevation;

Fig. 4 is a cross section taken substantially on the line 4—4 of Fig. 1 illustrating the type action, the universal bar for actuating the escapement mechanism, the carriage and the slidably mounted platen standard supported from the carriage as well as the ribbon actuating mechanism;

Fig. 5 is a cross section taken substantially on the line 5—5 of Fig. 1, showing one of the platen setting key levers and its association with the variable back spacing mechanism as well as the platen elevating mechanism;

Fig. 6 is a fragmentary vertical section taken longitudinally of the machine substantially along the line 6—6 of Fig. 5 looking in the direction of the arrows, this view illustrating the variable back spacing mechanism as well as the platen elevating mechanism to good advantage;

Fig. 7 is a detail view showing the front of the sheet holding tray of the platen with the writing apertures formed therein and also showing the ribbon elevating and guiding means as well as the platen-position-indicating means;

Fig. 8 is a detail view looking toward one end of the type-writer frame or case and illustrating the bell and the trip means connected with the platen for actuating the same;

Fig. 9 is a detail view showing a suitable manner in which the type-bar-actuating rock shafts may be trunnioned in the ends of the typewriter case or frame;

Fig. 10 is a detail cross section taken through the ribbon winding shaft and showing the ratchet and pawl driving means therefor, and

Fig. 11 is a detail view showing in section one of the small gear cases at each end of the typewriter frame wherein the ribbon spindle and its worm gear connection with the ribbon winding shaft are mounted.

In the embodiment of our improved typewriter illustrated, a suitable case or frame is provided, comprising a horizontal bottom plate 15 supported as shown upon short legs 15a constructed of rubber or other elastic sound-insulating material. Vertical frame ends 16 are rigidly secured to bottom plate 15 and are reinforced and secured together at their upper edges by an ornamental stringer plate 17 as well as by the heavy carriage-supporting-bar 18. The front of the typewriter case or frame is closed by a detachable front plate 19 and the rear of the case is provided with a detachable back 20.

A type-nest-supporting bar 21 (as shown of angular cross section) extends longitudinally and medially of the case and has its ends rigidly connected to the case ends 16 and on the vertical flange of said bar are mounted four identical type nests disposed adjacent the top of the case or frame and each comprising a vertical segment plate 22 carrying an inverted segment 22a which is slotted radially to accommodate the inner ends of a series of swingable type bars 23. The several type bars of each nest are pivoted between the slotted portions of the segment by suitable means such as an arcuate rod 24. The type heads 23a at the outer ends of the type bars normally rest (as shown in Figs. 4 and 5) against supporting sectors 25 disposed at the front of the type nests and rigidly secured to the segment plates 22.

The carriage as shown is in the form of a heavy substantially T-shaped plate 26, Fig. 3, disposed in a vertical plane and having its stem portion 26a depending to a point slightly above the bottom plate 15 of the case. The ends of the cross head or T arms of the carriage carry hanger brackets 27 which are each provided with a pair of cooperating rollers 27a for engaging the top and bottom portions of the carriage supporting bar 18. The cross head of the carriage 10 is disposed at substantially the level of the type nests.

Carriage 26 carries an elongated platen in the form of a flat vertical plate 28 having a facing of fiber board or equivalent, somewhat compressible material for receiving the impact of the type bars. Platen 28 is secured to the upper end of a vertical standard 29 which is disposed forwardly in alignment with the depending stem 26a of the carriage. Platen 28 is connected with carriage 26 for vertical sliding movement thereon and, as shown, is provided with a tubular slider 28a, Fig. 4, which is slidably disposed upon a vertical rod 30, said rod being secured at its upper end to carriage 26 and having its lower portion also connected with the depending portion of stem 26a of the standard. The lower extremity of said rod carries a roller 30a which works in suitable guides provided on the bottom plate 15 of the case or frame (best shown in Fig. 6). Platen 30 28 carries at its front side a vertical sheet holding tray 31 having a converging entrance at the top thereof to facilitate entrance and removal of the sheet of writing material. The front of tray 31 is provided with four typing apertures 31a, 31b, 31c and 31d, respectively, corresponding to the four type nests and one of said apertures, to wit:—aperture 31b, is somewhat wider than the others in order that the writer may conveniently view the typing effected on the sheet therethrough while the work is being done. A viewing aperture 31e may be formed adjacent the left end of the tray 31 to expose the subscriber's or client's name and address. The typewriter ribbon 32 is stretched longitudinally across the front of platen tray 31 having its respective ends wound upon conventional ribbon spools 33 which are rotatably mounted in spool housings 34 rigidly secured to the ends of the frame adjacent the upper edges thereof. Ribbon 32 is guided and moved laterally by suitable ribbon guides 35 and a central double guide 36, all of which are fixed to a horizontal rock shaft 37 by suitable arms 37a said rock shaft being journaled in bearings carried at the rear of the stringer plate 17. 55

A removable front cover plate 38 extends from the front plate 19 of the case or frame to the stringer plate 17 protecting most of the working parts exposed forwardly of the platen while a removable rear cover plate 39 extends from the 60 detachable back of the case to the rear of platen 28 having an off set portion 39a which encloses the carriage and hanger brackets. A U-shaped hand rest 40 is rigidly connected with the front of the case or frame and the type keys, platen setting keys and spacer bar are mounted above this rest and inwardly disposed therewith.

One set of key levers 41 is provided for actuating the several sets of type bars. Said key levers, as best shown in Figs. 2 and 4, normally extend horizontally and transversely of the case or frame and are pivoted at their inner ends to a common pivot rod or shaft 42. The typewriter action includes a series of parallel rock shafts 43, one being provided for each of the key levers 41. Each 75

of said rock shafts has fixed thereto, as shown, four upstanding rocker arms 44 which operate four type bars of the several type nests carrying the same type characters. The rock shafts 43 extend longitudinally across the interior of the case or frame and may be suitably journaled or trunnioned as shown in Fig. 9 by means of trunnion screws 43a having intermediate threaded portions screwed through the frame ends 16 and having cylindrical inner extremities upon which the ends of the rock shafts are rotatably mounted. Each of the rock shafts 43 has affixed thereto a substantially horizontal rocker arm 45 which is connected by a vertical link or links 46 with one of the key levers 41 at a point outwardly of the fulcrum 42. The upstanding rocker arms 44 are each connected by a link or rod 47 with a short depending bell crank arm extending below the fulcrum of one of the type bars 23. Links or rods 47 may include turn buckles 47a for adjustment purposes, if desired. Each of the rock shafts 43 is urged to extreme rearwardly rocked position by a coiled spring 44a connected eccentrically with a hub of one of the rocker arms 44 and anchored to a suitable bracket.

Carriage 26 is moved progressively toward the left hand end of the machine (Figs. 1, 2 and 3) by means of a spring actuated upstanding lever 48 mounted at the rear of the case and connected with the carriage by a link 49. A strong coil spring 50 urges carriage moving lever 48 toward one end of the case or frame and a suitable escapement mechanism controls the step by step movement of the carriage as the type keys or spacer bar are depressed.

The escapement mechanism is more or less conventional and therefore will not be described in detail. Suffice it to say that the escapement is mounted on an upstanding frame 51 fixed to the bottom plate 15 of the case and disposed behind the depending stem 26a of the carriage. The escapement wheel 52 is conventional except that it has one tooth missing at "x" for the purpose of double spacing for the decimal point, as will hereafter be more fully explained. Escapement wheel 52 is controlled by the usual pair of co-operating pawls 53 and 54 which are successively operated by the escapement lever 55 fixed to pawl 53, pawl 54 being retracted by a small striker disk carried by pawl 53. The outer end of escapement lever 55 projects laterally of the depending stem 26a of the carriage standard, is urged downwardly by a small coil spring and is actuated by a swingable universal bar 56 which extends transversely below all of the type key levers 41 and which has an actuating arm 56a Fig. 2 extending rearwardly and having an angular extremity 56b disposed behind the stem 26a of the carriage and underlying the escapement lever 55. The universal bar 56 also carries a narrow rearwardly projecting arm 56c which underlies a pin 57a carried by a ribbon shaft driving lever 57 (see Figs. 3 and 4). A ribbon winding shaft 58 extends longitudinally through the medial portion of the typewriter case and is suitably journaled in the frame ends 16, the ends of said shaft being enclosed within the worm gear cases 59 at the respective ends of the case and being provided with worms 58a which drive worm gears 60a fixed to the lower ends of ribbon spool spindles 60. A ratchet and pawl driving device 61, as illustrated in Fig. 10, is mounted on the ribbon winding shaft 58 having an arm 61a which is connected with the ribbon shaft driving lever 57 by means of a link 62. A retaining pawl 63 is pivoted to a suitable

bracket spaced some distance from the driving device 61 and engages a ratchet 64 fixed to ribbon winding shaft 58 to prevent backward turning of said shaft. The ribbon guides 35 and 36 are swung upwardly with rock shaft 37 by a rod 37a connected with universal bar 56.

A double space bar lever 65 extends transversely of the typewriter case or frame at the right hand side of the type key levers and is pivotally mounted at its inner end to a suitable upstanding bracket 66 mounted in the rear and at the right hand end of the case (see Figs. 3 and 4). Space lever 65 carries a laterally projecting arm 65a projecting from the left longitudinal edge thereof which overlies the universal bar 56 and serves to depress said universal bar when the space bar is depressed.

As has been previously stated, the platen standard 29 is mounted for vertical sliding movement upon the vertical slide rod 30 carried by the depending stem of the carriage. By reference to Figs. 3 and 6 it will be seen that the platen standard 29 is provided with a step or ledge 29a adjacent the lower end thereof which is supported by a platen elevating lever 67 carrying a roller 67a at its free end for engagement with said ledge and pivoted to a pin 68 at its opposite end. Pin 68 as well as most of the mechanism for progressively elevating the platen and for back spacing the platen and carriage is mounted in a vertical rectangular frame 69 supported from the bottom of the case adjacent the left hand end and rear portion thereof. The platen standard 29 and platen 28 are counter-balanced by means of a suitable coil suspension spring 70 connected with platen elevating lever 67 at a point disposed inwardly of its pivot and secured at its opposite end to a supporting bracket 69a. Platen elevating lever 67 carries at its intermediate portion a cam engaging roller 71 which rides the edge of a heart-shaped cam 72, said cam being affixed to a short shaft 73 journaled in frame 69. A ratchet wheel 74 is fixed to the rear end of shaft 73 and is actuated step by step by a pawl or tooth 75 carried by the upper end of an arm or rod 75a which is secured to a short universal bar 76 which traverses the upper edges of the rear ends of four platen setting key levers 77. Key levers 77 are fulcrumed in a slotted upstanding frame 78 which is secured to the bottom plate 15 of the case medially of the front and rear of the machine and spaced some distance from the left end of the machine. The rear ends of platen setting key levers 77, as shown, are curved downwardly and then horizontally, normally lying flush against the bottom plate 15 (see Fig. 5). In the embodiment of our invention illustrated four platen setting levers 77 are utilized, each being adapted to elevate the platen one line at a time and each back spacing the carriage and platen a different predetermined distance for alignment with a certain vertical column. If desired to print figures or characters in more than five columns, additional setting levers may be provided, all within the scope of our invention. The heart cam 72 is so shaped that upon step by step rotation of the same it will raise platen elevating lever 67 a predetermined distance for each progression of ratchet wheel 74, thereby lifting the platen standard and platen a line at a time for each depression of one or the other of the platen setting keys.

Mechanism is provided for variably back spacing the carriage and platen in accordance with the particular platen setting key depressed, said

mechanism being also actuated by the upward swinging movements of the rear ends of the key levers 77. To this end (see particularly Figures 3 and 6), a bell crank lever 79 is mounted in the rear of the machine adjacent the depending arm or stem of the carriage and has a substantially horizontal arm 79a which overhangs the rear ends of the several platen setting key levers and a substantially vertical arm 79b which is disposed adjacent the stem 26a of the carriage carrying at its upper end a camming roller 80 which is adapted to engage one edge of the carriage stem 26a to push the carriage toward one end of the frame when bell crank lever 79 is swung in counter-clockwise direction, as shown in Fig. 3. The lower edge of the arm 79a of the bell crank lever is notched, as shown in Fig. 6, to provide steps, each of which is disposed a different distance above one of the platen setting key levers 77. It will thus be seen that, assuming all of the said key levers to have the same throw, bell crank 79 will be swung a different predetermined distance by operation of each lever. A stop or guard mechanism 81, as shown, cooperates with the back spacing bell crank 79 to prevent irregularity or inaccuracy of the back spacing when one of the platen setting keys is depressed violently. As shown, said guard mechanism includes a bell crank 81a having a vertical arm which carries a yieldable stop plate 81b for engagement with the edge of the carriage stem 26a. The second arm of bell crank 81a is disposed beneath guard actuating lever 82 which may be pivoted to the same supporting bracket as back spacing bell crank 79 and which has one end thereof traversing and overlying the rear ends of platen setting key levers 77. Said overlying end of guard actuating lever 82 is notched, as clearly shown in Fig. 6, to form steps located above the several key levers 77 in such relation that the upward swinging movement of the rear end of each key lever will swing actuating lever 82 through a different predetermined movement, lever 82 producing various predetermined movements of the guard mechanism 81 in accordance with the particular platen setting key depressed.

To indicate to the operator of our typewriter, the typing position of the carriage and platen at any time, we provide on the exterior and central portion of the platen sheet-holding tray a number of dots, perforations or other indicia 83 (see Fig. 7) which are arranged in vertical columns and also horizontal rows corresponding in number and arrangement to the printing spaces on the sheet or platen in which our typewriter can print. A stationary indicator arm 84 cooperates with the indicating elements 83 and may be supported from the type nest supporting bar 21 extending upwardly medially of the frame or case and having a free extremity which is disposed at all times just over one element 83 and indicating the line and column where the next figure is to be typed.

Operation

The typewriter illustrated is adapted to type five columns of figures in six rows or lines, although it will, of course, be obvious that the number of columns and lines may be greatly multiplied and alphabetical characters employed as well as figures, all within the scope of our invention.

Sheet writing material is disposed vertically in platen tray 31 against the platen 28 and is preferably in the form of an elongated sheet, which

may be of bill form, proportioned to nicely fit the tray. If desired, of course, separate sheets may be utilized for each original typed, in which instance it would be desirable to provide a series of attachment clips at the top of the platen tray. 5

Assuming the platen 28 in its lowermost position, at which time the platen supporting lever 67 is supported by its roller 71 by the notch of the heart shaped elevating cam and assuming the first entry to be made is "\$125.36", the platen 10 setting key bearing the indicia "100" (see Fig. 2) is depressed, thereby swinging its key lever 77 to elevate universal bar 76 which steps the ratchet 15 74 one notch and elevates the platen one line. The upward swinging of the rear end of the platen 15 setting key lever 77 simultaneously actuates the back spacing mechanism, including the bell crank 79 and the variable stop or guard actuating lever 82. Since the "hundreds" column setting key was depressed, the lowest step on the overhanging edge of bell crank 79 is engaged by the "hundreds" key lever and bell crank 79 is swung through its maximum movement pushing the standard to its right hand limit of movement. The guard actuating or carriage stop lever 82 is 20 not moved by the operation of the "hundreds" setting key. The platen with the work sheet thereon is thus automatically disposed for printing the first entry and the typing keys "1", "2", "5", "3" and "6" are successively depressed, 25 visibly typing the desired entry on the sheet through the four type apertures 31a, 31b, 31c and 31d. The first decimal figure "3" printed is spaced an extra space from the unit figure "5". This is automatically effected by the construction of the 30 escapement wheel 52, this wheel, as has been previously stated, having one of its teeth missing at "X". The escapement operation is thought obvious and needs no further explanation. In the operation of the action, the type key lever rocks 35 the appropriate operating shaft 43 which through its multiple connections comprising rock arms 44 and links 47 actuate the corresponding type bars 23 of the four nests of type. The universal bar 56 operates the driving mechanism for the ribbon 40 winding shaft 58, which shaft in turn winds the ribbon spools in opposite directions. The universal bar 56 also swings the arms 31a of the ribbon guides upwardly slightly before the impact of the type. 50

Assuming the next entry to be made is "\$1.72", the unit platen shifting key bearing the numeral "1" is depressed causing the platen to be elevated one line and causing the carriage and platen to be simultaneously back spaced for 55 proper alignment with the unit column. The unit key lever at its rear end in this instance actuates not only the bell crank back spacing lever 79, but also the guard actuating or variable carriage stop lever 82, the guard or stop mechanism cooperating with the roller of bell crank 79 to prevent inaccuracies in the proper positioning of the carriage and platen. 60

When the platen is in its uppermost position, platen elevating lever 67 is supported upon the heart cam 72 adjacent the apex thereof. The next progressive movement of the ratchet wheel 64 disposes the roller 71 of the lever on the sharp incline at the opposite side of the cam causing the cam and ratchet wheel to slip through substantially one-half of a revolution until the roller 71 is seated in the notch at the top of the heart, whereupon the platen will be again disposed in its lowermost position and set for the particular entry to be made at that time. 75

The particular writing position of the platen at any time in the operation of our typewriter may be quickly ascertained by means of the co-operating indicating elements 83 and 84.

5 From the foregoing description it will be seen that we have provided an efficient typewriter which will print simultaneously a series of originals or duplicates and wherein the position of the platen or work holder may be automatically 10 set, both with reference to line setting and column setting by operation of the appropriate setting key.

15 It will, of course, be understood that various changes may be made in the form, details, proportions and arrangement of the parts, without departing from the scope of our invention, which, generally stated, consists in a device capable of carrying out the objects above set forth and in the novel parts and combinations of parts disclosed and defined in the appended claims.

20 What is claimed is:—

1. In a typewriter, a progressively movable carriage, a platen mounted on said carriage and back spacing mechanism comprising a key lever, an 25 actuating lever for backwardly moving said carriage, said actuating lever having an arm disposed in the path of said key lever whereby a predetermined swinging movement of said key lever will back space said carriage a predeter-

mined distance, variable carriage stop or guard mechanism associated with said back spacing mechanism and comprising also a lever having an arm disposed above said key levers and so related to said key levers that it will be swung different predetermined distances by said several levers and a movable guard or stop selectively positioned for engagement with said carriage by said carriage stop actuating lever.

2. In a typewriter, a progressively movable carriage, a platen mounted on said carriage and back spacing mechanism comprising a key lever, an actuating lever for backwardly moving said carriage, said actuating lever having an arm disposed in the path of said key lever whereby a predetermined swinging movement of said key lever will back space said carriage a predetermined distance, variable carriage stop or guard mechanism associated with said back spacing mechanism and comprising a member disposed 20 above said key levers and so related to said key levers that it will be moved different predetermined distances by said several levers and a movable stop selectively positioned for engagement with said carriage by said carriage stop actuating lever.
